UNITED STATES PATENT OFFICE

125,436

DESIGN FOR A STIRRUP FOR SADDLES OR
THE LIKE

Benjamin F. Talbert, Pennville, Ind.

Application October 24, 1940, Serial No. 96,035

Term of patent 14 years

To all whom it may concern:

Be it known that I, Benjamin F. Talbert, a citizen of the United States, residing at Pennville, in the county of Jay and State of Indiana, have invented a new, original, and ornamental Design for Stirrups for Saddles or the like, of which the following is a specification, reference being had to the accompanying drawing, forming part thereof.

Figure 1 is a perspective view of a stirrup for saddles or the like, showing my new design,

I claim:

The ornamental design for a stirrup for saddles or the like, as shown.

BENJAMIN F. TALBERT.
